UNITED STATES PATENT OFFICE.

FORD W. HARRIS, OF LOS ANGELES, CALIFORNIA, ASSIGNOR TO PETROLEUM RECTIFYING COMPANY, OF SAN FRANCISCO, CALIFORNIA, A CORPORATION OF CALIFORNIA.

STARTER FOR ELECTRICAL DEHYDRATORS.

Application filed November 1, 1920. Serial No. 420,980.

To all whom it may concern:

Be it known that I, FORD W. HARRIS, a citizen of the United States, residing in the city of Los Angeles, county of Los Angeles, State of California, have invented a new and useful Improvement Comprising the Starters for Electrical Dehydrators, of which the following is a specification.

My invention relates to dehydrators in which electric current is used to cause the emulsified water, carried in emulsions of oil and water, to agglomerate into large water masses which settle out readily by gravity or which may be separated by centrifuges or other means. I have found that it is possible by operating such dehydrators upon emulsions having a low percentage of water to handle large volumes at a low cost but in many cases I have found that when dehydrators, designed to be operated in such a manner, are filled with very wet emulsions that it is difficult if not impossible to get them to start to operate properly due to the inherent tendency of water rich masses to collect in the electric field where they conduct current indefinitely greatly reducing the effective voltage and rendering the apparatus inefficient if not absolutely inoperative.

I have further found that it is comparatively easy to dehydrate emulsions in which the water is present in the form of coarse particles but that where a considerable portion of the water is in the form of what may be termed ultra-microscopic particles that it is very difficult to initiate the dehydrating action due, I believe, to the fact, that innumerable high resistance paths form through the body of the emulsion through which current flows. The current flowing in any single path is of course exceedingly minute but the aggregate current flowing through all such paths is sufficient to form a short circuit which will throw out the circuit breaker if the apparatus is provided with one. In the event that the circuit is protected by reactance or resistance the effect of this short circuit is to reduce the voltage between the electrodes of the dehydrator to practically zero so that the dehydrating action ceases. Many types of dehydrators which are quite successful on coarse emulsions cannot be started on fine emulsions due to this tendency to short cir-

cuit. I think that the principal difficulty in this respect is due to fine water particles and not to the percentage of water as I have found that the tendency to short circuit in very wet emulsions is no greater than the tendency to short circuit in some emulsions in which the percentage of water is very small, in fact I have known cases in which dehydrators, which operated very well on emulsions in which the total water content was approximately thirty per cent, would short circuit on oil of the same characteristics when it contained only one-half of one per cent of emulsion as indicated by the centrifuge. This percentage of emulsion does not, however, correctly indicate the true water content which may have been less than one-tenth of one per cent. Such very fine emulsions are produced where a coarser emulsion is boiled down or where the water in the emulsion has traveled for a long distance through oil sands in company with the oil and has therefore been thoroughly broken up and mixed with the oil. In most types of dehydrators with which I am familiar, however, there is little difficulty in operating them once they start to function as they operate wholly by agglomeration and produce their own coarse emulsion once they are started, the fine emulsion mixing therewith and being readily disposed of thereafter.

Previous inventors have not recognized the fact that the difficulties met with in the practical operation of commercial types of dehydrators have been due in many cases to fine emulsion nor have they recognized that it was very difficult if not impossible to provide proper conditions for starting on fine emulsions and thereafter running on the coarser emulsions formed in the electric field between the electrodes without changing the adjustment of the apparatus. Many failures of electrical dehydrators are due to the fact that it has been thought necessary to design them so that they would operate on all sorts of oil and would be self starting.

An object of my invention is to provide a dehydrator which shall be provided with means by which it may be started on very wet or fine emulsions but in which entirely different means are provided for normal running.

Further objects and advantages will be made evident hereinafter.

In the drawing which is for illustrative purposes only,

5 Fig. 1 is a side elevation partly in section and Fig. 2 is a plan, of a convenient embodiment of my invention.

In this form of my invention, which is one of many, 11 is a tank having a tight top and 10 bottom and having suspended therein an electrode 12. This electrode is cylindrical and is spaced concentrically with the tank 11, which is also cylindrical, the space between the electrode and the tank forming 15 the electric field 13 in which the dehydration takes place when the apparatus is operating normally. The electrode 12 is suspended from an insulator 14 and from a rod 15, which passes through an outlet bushing 16, being connected through a suitable switch 17 with the secondary of a transformer 18 the other side of which is connected to the tank 11 through a wire 19. Oil is delivered to the tank 11 through a 20 raw oil inlet pipe 20, clean oil being withdrawn through a clean oil outlet pipe 21, and waste water being withdrawn through 25 a water outlet pipe 22 to a drain 23.

If coarse emulsion is available the tank 30 may be filled therewith through the pipe 20.

The electric field 13 acting on large particles agglomerates them further so that they fall out of the field into the bottom of the tank from which they may be withdrawn 35 in the form of free water through the pipe 22, the cleaned oil being withdrawn through the pipe 21. In the event, however, that the emulsion is very fine the small water particles will build up a short circuit between 40 the electrode 12 and the tank 11 and the dehydrating action stops due to the loss of voltage in the tank as has previously been explained. It is then necessary to have recourse to some other means of producing 45 enough coarse emulsion to allow the dehydrator to start. This emulsion I prepare by means of what might be called a starting dehydrator.

This starting dehydrator consists of a 50 shell 30 having a tight top in which is placed an outlet bushing 31 which carries an inner electrode 32, the outer end of which is connected through a switch 29 to the secondary of the transformer 18. Passing through the 55 bottom of the shell 30 is an outer electrode 33 which is in the form of a pipe whose lower end is connected to the discharge of a centrifugal pump 34 which is driven by any suitable motor not shown. The pump 60 34 takes emulsion from below the electrode 12 and delivers it at a high velocity to the space between the inner electrode 32 and the outer electrode 33. The outer electrode 65 is flared out to pass up and around the lower end of the outlet bushing 31 the emulsion

passing therethrough and being delivered from the shell 30 to the upper part of the tank 11 through a pipe 35.

By passing the fine emulsion through the space between the inner and outer electrodes at a high rate of speed the formation of permanent paths through the fine emulsion is prevented and it is possible to maintain high voltage between the electrodes. The rate of dehydration is not as 75 rapid as in the main dehydrator but it is possible to continuously agglomerate water which tends to gradually bring the average size of the water particles in the tank 11 up until they are large enough to make 80 dehydration in the field 13 possible. It is then possible by throwing over the switch 29 to disconnect the electrode 32. The switch 17 which has previously been open is then closed to connect the rod 15 to start 85 the main dehydrator at which time the pump 34 can be stopped. Under ordinary conditions the apparatus then can be run indefinitely by supplying raw oil through the pipe 20 drawing off clean oil through the outlet 90 pipe 21 and water through the pipe 22.

In some cases it is desirable to operate both the starting and the main dehydrators simultaneously the starting dehydrator being most efficient on the finer emulsion which 95 rises to the top of the tank 11 and the main dehydrator acting on the coarser emulsion which is at lower levels. It is evident that this can be done by starting with the switch 17 open and the switch 29 closed running 100 until coarse emulsion is built up in the tank 11 and then closing the switch 29. The two dehydrating actions then take place simultaneously and as soon as the water percentage in the top of the tank 11 reaches the 105 desired minimum oil can be started in through the pipe 20 the apparatus thereafter functioning automatically.

It should be noted that the main dehydrator contained in the tank 11 and the 110 starting dehydrator contained in the shell 30 operate upon somewhat different principles. The main dehydrator operates upon the principle of subjecting a practically stationary or at least a very slow moving body 115 of emulsion to the action of electric current in such a manner that the current paths are automatically disrupted as fast as they form. This is only possible when the individual paths are of sufficiently low resistance to allow enough current to flow to 120 vaporize portions of that path so that the flow of current is interrupted without the necessity for any mechanical means for interruption. This method of operation is 125 only possible when the water consists in whole or in part of large drops. The agglomeration produced by any flow of current, of course, produces larger drops which fall out by gravity from the field leaving 130

the smaller drops to form new paths which are in turn disrupted by the flow of current.

In the starting dehydrator, however, I do not depend on the action of the current to break up the paths but break them up mechanically due to the rapid flow of liquid through the field. I also do not depend on settling action to remove the free water from the field, but on the contrary I remove the water forcibly by the rapid flow, the agglomerated water being delivered in company with the oil into the main tank 11 in which the water settles out from the oil in some measure so that only the finer particles are again delivered to the field. When therefore the starting dehydrator has been operating for some time the character of the emulsion will be materially changed in that the average size of the water particles will be very considerably increased and the total amount of water will be somewhat reduced by the settling out of agglomerated water so that the main dehydrator can then be started operating automatically thereafter without the need for mechanical agitation.

I employ on the ordinary types of California emulsions an alternating potential of 11000 volts.

30 I claim as my invention:—

1. The process of dehydrating emulsions which comprises circulating emulsion from a bulk supply through an electric field at such a velocity that the formation of permanent short circuit in that field is prevented and thereafter subjecting the coarse

emulsion so formed in the bulk supply to the action of a second electric field in which the disruption of the current paths occurs automatically without mechanical agitation. 40

2. A dehydrator comprising a tank adapted to hold a bulk supply of the emulsion to be treated; a starting dehydrator; means for forcibly circulating emulsion 45 from said bulk supply through said starting dehydrator and back to said bulk supply; and means for producing an electric field in said bulk supply.

3. A dehydrator comprising a settling 50 tank; means for drawing water off from the bottom of said tank; a starting dehydrator; means for circulating emulsion from said settling tank through said starting dehydrator and back into said settling tank; and 55 means for subjecting the coarse emulsion produced by said circulation to the action of an electric field located in said settling tank.

4. A dehydrator comprising a settling 60 tank; electrodes in said tank; a shell; starting electrodes in said shell; means for circulating emulsion from said tank through said shell and back to said tank; means for applying an electromotive force between 65 the electrodes in said tank; and means for applying an electromotive force between said starting electrodes.

In testimony whereof, I have hereunto set my hand at Los Angeles, California, this 70 5th day of December, 1919.

FORD W. HARRIS.
